UNITED STATES PATENT OFFICE.

HENRY J. KELLEY, OF CARNEGIE, PENNSYLVANIA.

REFRIGERATOR FOR MEAT-WAGONS.

SPECIFICATION forming part of Letters Patent No. 611,491, dated September 27, 1898.

Application filed August 19, 1897. Serial No. 648,752. (No model.)

To all whom it may concern:

Be it known that I, HENRY J. KELLEY, a citizen of the United States of America, residing at Carnegie, in the county of Allegheny and State of Pennsylvania, have invented certain new and useful Improvements in Refrigerators for Meat-Wagons, of which the following is a specification, reference being had therein to the accompanying drawings.

This invention relates to certain new and useful improvements in refrigerators for meat-wagons and might be considered in connection with an application for a similar patent filed by me April 6, 1896, Serial No. 586,509.

The invention has for its object to provide a refrigerator which may be placed in position in an ordinary meat-wagon and removed therefrom as desired without necessitating any change in the construction of the wagon.

The invention further aims to construct a refrigerator for this purpose that will enable the driver of the wagon to reach any portion of the interior of the refrigerator from his position on the seat and thereby considerably reduce his labors.

A further object is to so arrange the refrigerator that the customers may be permitted to inspect all the contents of the cooling-boxes from their position at the rear of the wagon.

The invention further aims to provide special compartments, being adapted to be used for special orders, which are thus not exposed to the outside air through the opening of the doors of the cooler.

A still further object is to construct a refrigerator as described that will be extremely simple in its construction, strong, durable, and effectual in the performance of all its functions.

With the above and other objects in view the invention finally consists in the novel construction, combination, and arrangement of parts to be hereinafter more specifically described, and particularly pointed out in the claim.

In describing the invention in detail reference is had to the accompanying drawings, forming a part of this specification, and wherein like letters of reference indicate

similar parts throughout the several views, in which—

Figure 1 is a longitudinal sectional view of the body of the wagon and of my improved refrigerator therefor. Fig. 2 is a perspective view of the refrigerator. Fig. 3 is a sectional view taken on the line X α of Fig. 2.

Referring now to the drawings, a a represent the two cooling-boxes, which are at each side of the refrigerator and extend upward a considerable distance above the ice-chests, so as to form a passage-way between the two boxes, and have arranged therein the hooks b , upon which to hang the meat, said hooks being securely fastened on the cross-piece c , or they may be attached to the side walls d or arranged thereon in any other suitable manner. The central box e , formed by extending the cooler-boxes a above the same at the sides, is provided with doors f , preferably arranged at a slight incline, as shown, and, if desired, may be provided with glass windows, so as to expose the contents to view without opening the doors.

The screen g at the forward end of the box e is provided with apertures h and permits the gradual admission of cool air to the compartment k without exposing the contents of said compartment to the sudden entrance of outside air when the doors of the cooling-boxes are opened. The lid l of the compartment k may serve as a seat for the wagon.

At the rear of the boxes a the same are provided with doors a' , and a wire-netting a'' is provided within these boxes, so as to divide the same and form a receptacle b' for the ice, said cooling-boxes being provided on their side adjacent to the passage-way with doors c' , which may be fastened by ordinary latches c'' , secured to the frame of door and engaging in staples d' in the sides of the boxes.

The ordinary swinging end-gate e' and curtain e'' are employed for closing the rear of the wagon.

It will be observed that when the ice is placed in the receptacles provided therefor the cold air is permitted to pass into the cooling-boxes containing the meat, and is also permitted to pass through the apertures h into the special compartment k formed under the seat.

All portions of the interior of the cooler

may be readily reached by the driver from his position on the seat, and the opening of the door *c'* to remove the meat will not affect the compartment *k*, as the outside air will 5 not be permitted to come in contact with the contents of the same. The floor *k'* may extend solid the entire width of the refrigerator and the outer walls cut so as to form one wall of the cooler-box and one wall of the 10 special compartment, as is fully illustrated in Fig. 2.

It will be noted that various changes may be made in the details of construction without departing from the general spirit of my 15 invention.

Having fully described my invention, what I claim as new, and desire to secure by Letters Patent, is—

The combination with the central box or 20 compartment having a top or cover, of side

compartments or cooling-boxes rising above the top of the central compartment and provided with doors in their inner walls, an ice-compartment at the rear end of each cooling-box, a provision-compartment in front of the 25 cooling-boxes, and separated from the latter by a screen, whereby the cold air from the cooling-boxes will freely pass to the special compartment, but the contents of the latter will not be exposed to the outer air by the 30 opening of the doors of the cooling-boxes; and a cover for said special compartment constituting the seat of the wagon.

In testimony whereof I affix my signature in presence of two witnesses.

HENRY J. KELLEY.
